(57) **CLAIM**

The ornamental design for an automotive tire, as shown and described.

DESCRIPTION

FIG. 1 is a front perspective view of an automotive tire;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an enlarged view of section A-A shown in FIG. 2; and,

FIG. 9 is a cross-sectional view taken along line B-B shown in FIG. 8.

The broken lines in the drawings depict portions of the automotive tire that form no part of the claimed design. The hatching of FIG. 9 also forms no part of the claimed design.
